UNITED STATES PATENT OFFICE.

GEORGE F. LELANSKY, OF CANTON, OHIO.

GARMENT ATTACHMENT.

1,172,615.

Specification of Letters Patent. Patented Feb. 22, 1916.

Application filed July 20, 1915. Serial No. 40,851.

To all whom it may concern:

Be it known that I, GEORGE F. LELANSKY, a citizen of the United States, residing at Canton, in the county of Stark and State of 5 Ohio, have invented a new and useful Garment Attachment, of which the following is a specification.

The present invention relates to means for preventing the lower part of the under- 10 garment or shirt from creeping upward on the body of the wearer and has special reference to two-piece undergarments, but it will be understood that the present invention need not necessarily be confined to undershirts exclusively.

The objects of the present invention are, first, to prevent the discomforts caused or produced by the creeping or upward movement of the undergarments; and second, to 20 provide simple means whereby the lower portion and especially the portion of the undergarment below the waist line is held in its proper position under all circumstances. These objects, together with other 25 objects readily apparent to those skilled in the art, may be attained by the construction illustrated in the accompanying drawings, although the invention may be embodied in other forms, the construction illustrated being chosen by way of example.

In the accompanying drawing:—Figure 1 is a side view of a shirt or undergarment. Fig. 2 is a similar view of the drawers. Fig. 3 is a sectional view showing the drawers and shirt connected together, said connection being below the waist line of both undergarments. Fig. 4 is a front view showing the top or upper portion of the drawers and illustrating the usual drawers 40 supporting straps and a portion of one of the suspender straps placed in position to support the drawers.

Similar numerals of reference indicate corresponding parts throughout the several 45 figures of the drawings.

In the accompanying drawing, 1 represents an undershirt or the top garment of a two-piece suit. The particular pattern of this garment does not enter into the present 50 invention so far as its detail construction is concerned. 2 represents the lower or drawers member of the two part suit, which within itself has no particular reference to the present invention and may be of any 55 style or kind.

For the purpose of carrying out the ob-

jects of the invention above pointed out the extreme bottom of the shirt or upper undergarment is provided with the pendent tabs 3, which are located upon opposite 60 sides of the garment. The lower member of the two part suit, to-wit: The drawers are provided with normally upwardly extending tabs, said tabs being located below the top or waist line of the drawers, the 65 position of the tabs 4 being such that when the tabs 3 and 4 are connected together, preferably by buttons the top of the drawers will extend some distance above the points where the tabs 4 are connected that 70 is to say the drawers will extend upward to the waist line but said tabs are not for the purpose of giving any support to the drawers above the point of the tabs 4.

It will be understood that when the tabs 75 3 and 4 are connected together the lower part of the shirt will be prevented from becoming twisted about the body of the wearer holding the part below the waist line from being rolled or gathered together 80 in a lump or roll at any one part, the primary object being to hold the shirt or undergarment in even contact with the body of the wearer, but at the same time without producing any pull or strain upon the waist 85 portion of the drawers or lower member of the two-part suit.

In the drawings I have illustrated tabs secured to the drawers and also to the shirt. This is preferable as it provides means for 90 a wider range of adjustment, but it will be understood that the objects of the present invention can be carried out by a different fastening means provided the fastening means are located in the positions whereby 95 the beneficial results are produced, but regardless of the specific fastening means such means should be and are to be located below the waist line of both pieces of the two-part suit, by which arrangement the 100 wearer experiences no annoyance or inconvenience of any kind, resulting from strains brought about by the movements of the wearer.

It will be understood that regardless of 105 the position of the wearer there is no direct pull or strain at the waist line of either garment, but at the same time the portion of the garment below the waist line, to-wit: The shirt is held down without any reference 110 to the coupling of the two-part garment at the waist line.

It will be understood that the fastening device secured to the drawers should be upon the inside so as not to interfere in any way with the upper member of the two-part suit.

Having fully described my invention what I claim as new and desire to secure by Letters Patent, is:

In a two-part garment, the combination of fastening means secured to the extreme

bottom of the upper member of the two-part suit and below the waist-line thereof, and fastening means secured to the inside of the lower member of the two-part garment and below the waist-line of said lower member.

In testimony that I claim the above, I have hereunto subscribed my name.

GEORGE F. LELANSKY.
